GUARD-RAIL.

1,173,420.

Specification of Letters Patent. Patented Feb. 29, 1916.

Application filed December 20, 1915. Serial No. 67,705.

To all whom it may concern:

Be it known that I, BENEDICT T. GIBBS, Jr., a citizen of the United States, residing at Chicago Heights, in the county of Cook and State of Illinois, have invented a certain new and useful Improvement in Guard-Rails, of which the following is a specification.

This invention relates to guard rails for tracks carrying moving vehicles, notably railroad rails.

The object of the invention is to provide a guard rail applicable to a track rail for a considerable distance, as over two or more ties, in which the guard rail itself and the devices for securing it in place are made in two or more pieces as distinguished from the one-piece devices of the prior art, so that the guard rail proper may be placed in position, removed and replaced with or without renewal of one of the parts as desired without its being necessary to remove and replace the major parts of the securing device.

The invention consists in a device for carrying out the foregoing objects, which can be easily and cheaply made and installed, which is satisfactory in operation and not readily liable to get out of order. Also in the features and details of construction hereafter more fully described in the specification and claims.

Referring to the drawings, in which similar numerals indicate the same parts throughout the several views, Figure 1 is a plan, and Fig. 2 is a side view of mechanism illustrating this invention in its preferred form. Figs. 3, 4 and 5 are transverse sectional detail views on the correspondingly numbered lines of Fig. 1. Fig. 6 is a perspective view of the guard rail proper removed from all other parts. Fig. 7 is a corresponding perspective view of the securing device. Fig. 8 is a sectional and perspective view showing the relations of the parts in assembled and finally adjusted position. Fig. 9 is a sectional detail view on the line 9-9 of Fig. 4, and Fig. 10 shows the device provided with a modified construction of slot 32.

The device of this invention is applicable to any sort of a rail over which a vehicle passes, and is here conventionally shown as applied to the rail 10 resting upon ties 12, in the ordinary manner. The guard rail, as a whole, 14, illustrated in Fig. 6, is, broadly

speaking, secured in place through the agency of the base plate 16 carrying the brace blocks 18, shown in perspective in Fig. 7. In the particular case here illustrated, this base plate 16 is made in one piece to 60 extend under the rail 10 over four ties 12, but obviously the length of this base plate may be varied without departing from this invention. The brace blocks 18 are rigidly secured upon the base plate 16 either by being made integral therewith, as shown, or by any other suitable means. They are preferably connected together by a vertical plate or flange 20 having therein at suitable intervals bolt holes 22. The base plate 16 is securable in adjusted position transversely of the rail and lengthwise of the tie through the use of spikes 24 passing through the angularly notched adjusting holes 28 provided for the purpose in the manner well known in 75 the art.

The top of each block 18 is cut away to form the horizontally inclined or wedge surface 30, the inclination of each of these wedge surfaces being substantially the same 80 and preferably, though not necessarily, at substantially the same height above the base plate 16.

Extending horizontally through the inner face of each brace block; viz., the face adjacent to the rail 10, and below the adjacent wedge surface 30, is a slot or recess, in the case illustrated in the principal figures the U-shaped recess 32 having its upper face 33 extending parallel to the base plate 16. A 90 modified form of this slot is shown at 80 in Fig. 10, in which the upper face is marked 33^a. These slots are preferably, though not necessarily, made with their upper faces 33 or 33^a substantially the same height above 95 the base plate.

The guard rail 14, heretofore referred to in general terms only, is preferably made in angular form with a horizontal tread flange 40 extending from a vertical flange 42. On 100 the under surface of this tread flange 40 are a plurality of depending blocks 44 having lower horizontal inclined or wedge surfaces 46 corresponding in angularity to the surfaces 30 of the brace blocks heretofore described. These surfaces 46 just described are so located on the underside of the flange 40 of the guard that when the parts are in assembled position, one of these wedge surfaces 46 bears upon an adjacent wedge sur- 110

face 30 on a brace block, as clearly shown in Fig. 9.

Extending from the vertical flange 42 of the guard rail and below each wedge surface 46, heretofore described, is a horizontally extending flange 50 of such a size, shape and location that it readily enters and slides in the horizontal slot 32 or 80 as the case may be, in the adjacent brace block.

10 As these horizontal flanges 50 are like the slots 32 or 100 parallel to the base plate 16 and the wedge surfaces 30 and 46 are inclined thereto, it is entirely obvious that it only takes a relatively short movement of 15 the guard rail 14 horizontally to the right, as viewed in Fig. 9, to effectually wedge the guard rail onto the brace blocks, and that corresponding movement of the guard rail in the opposite direction will release 20 this locking effect so that so far as the parts heretofore described are concerned at least, the guard rail may be removed from the brace blocks.

In order to insure the proper positioning 25 of the guard rail 14 with reference to the rail 10 and upon the brace blocks when the parts are in assembled position, the guard rail is provided with a plurality of horizontally extending separating lugs 54 located on the rail side of the guard rail, extending to the rail and engaging it under the rail head 56, as clearly appears in Fig. 4. In the particular case here illustrated, only 30 two of these members 54 are provided and 35 they are located directly opposite to the two central brace blocks. The position and length of these members 54 along the rail is not material to the operation of the device.

The guard rail is, as usual, bent outwardly 40 at its ends, as shown in Fig. 1, and is preferably provided with end foot guards 60 and 62 integral therewith. The ends of the guard rail are secured to suitably located ties by the brackets 64 and spikes 65 in the 45 ordinary manner.

The vertical flange 42 of the guard rail is so located with reference to the other parts heretofore described that, as clearly 50 appears in Fig. 5, it lies inside of and is 55 slidable horizontally along the plate or flange 20 connecting the brace blocks, and it is provided at suitable intervals with holes 68 adapted, when the parts are in finally 60 assembled position, to register with the holes 22, heretofore described, so that one or more bolts 70 may be inserted through these sets of holes, as shown, to rigidly secure the parts in position and prevent the guard rail wedge surfaces 46 from backing off from the 65 brace block inclined surfaces 30. In the drawings, three of these bolts 70 are shown, but a less number may be used without departing from the invention.

It should be noticed that the members 50 65 which, when the parts are in locked posi-

tion, engage the brace blocks heretofore described to prevent any vertical movement of the guard rail with reference to them are only slightly longer than the brace blocks themselves and are not as long as the distance between the respective brace blocks, the result being that when the guard rail has been moved from the position shown in Figs. 1 and 2 to the left until these members 50 are clear of their adjacent brace blocks, the guard rail can be lifted vertically upward and removed entirely from engagement with the rail and the brace block.

In the operation of installing the device, the base plate 16 with the brace blocks attached thereto is inserted under the rail 10 and adjusted as near as may be to what is supposed to be its final position. The guard rail 14 is then held with the members 50 between the brace blocks, and then lowered 85 into position with the upper flange 40 resting upon the tops of the brace blocks, the guard rail being tilted in the lowering operation to allow the members 54 to pass under the rail head 56. The guard rail and attached parts is now moved to the right until the parts assume the position shown in Figs. 1 and 2, the guard rail being driven horizontally to the right as hard as may be necessary to insure proper engagement of 95 the respective wedge surfaces 30 and 46, after which the bolts 70 are put in place. In practice, it may be desirable not to bore either the holes 22 or the holes 68, depending upon the material of which the respective parts are made, until the foregoing adjustments have been initially made. During the foregoing positioning of the parts, any 100 adjustments of the brace blocks needed may be made by changing the locations of the spikes 24 in the slots 28. When everything is finally adjusted, the brace blocks are finally secured in place by the driving of the spikes 74.

If, at any time, the guard rail needs repair or replacing, it can be removed by first taking out the bolts 70, driving the guard rail to the left, as viewed in Figs. 1 and 2, and lifting it out, all as has heretofore been more fully described.

Having thus described my invention, what I claim as new and desire to secure by Letters Patent, is:—

1. In combination with the main rail, a plurality of brace blocks secured adjacent thereto, and a guard rail having oppositely projecting members entering respectively the brace blocks and the space below the head of the main rail, for the purposes set forth.

2. The combination with the main rail, a plurality of brace blocks secured thereto, a guard rail supported by the brace blocks having oppositely projecting members entering respectively the brace blocks and the

- space below the head of the main rail, and means for rigidly securing the guard rail in said position.
3. The combination with the main rail, a plurality of brace blocks secured thereto, a guard rail supported by the brace blocks having oppositely projecting members entering respectively the brace blocks and the space below the head of the main rail, and wedge devices tightly securing the parts in said position.
4. The combination with the main rail, a plurality of brace blocks secured adjacent thereto, a guard rail supported by the brace blocks having oppositely projecting members entering respectively the brace blocks and the space below the head of the main rail, and wedge devices formed on the guard rail and the brace blocks for tightly securing the parts in position.
5. The combination with the main rail, a plurality of brace blocks secured adjacent thereto, a guard rail supported by the brace blocks having oppositely projecting members entering respectively the brace blocks and the space below the head of the main rail, and wedge devices formed on the tops of the brace blocks and on adjacent parts of the guard rail for tightly securing the parts in position.
6. In combination with a main rail, a plurality of brace blocks secured adjacent to the rail, along it, a substantially straight guard rail supported by the brace blocks at a distance from the main rail and slideable parallel to the main rail; means spacing the guard rail from the main rail; and means placed at intervals along the guard rail adapted, when the guard rail is in one position lengthwise of itself, to engage the brace blocks and secure the guard rail thereto while permitting ready removal of the guard rail from the brace blocks when the guard rail is moved lengthwise of itself to a certain other position.
7. In combination with the main rail, a plurality of brace blocks secured adjacent to the rail along it, a substantially straight guard rail supported by the brace blocks at a distance from the main rail and slideable parallel to the main rail; means spacing the guard rail from the main rail; and wedge devices placed at intervals along the guard rail adapted, when the guard rail is in one position lengthwise of itself, to engage the brace blocks and secure the guard rail thereto while permitting ready removal of the guard rail from the brace blocks when the guard rail is moved lengthwise of itself to a certain other position.
8. In combination with the main rail, a plurality of brace blocks secured adjacent to the rail along it, a substantially straight guard rail supported by the brace blocks at a distance from the main rail and slideable parallel to the main rail; means spacing the guard rail from the main rail; wedge devices placed at intervals along the guard rail adapted, when the guard rail is in one position lengthwise of itself, to engage the brace blocks and secure the guard rail thereto while permitting ready removal of the guard rail from the brace blocks when the guard rail is moved lengthwise of itself to a certain other position.
9. In combination with the main rail, a plurality of brace blocks secured adjacent to the rail along it, a substantially straight guard rail supported by the brace blocks at a distance from the main rail and slideable parallel to the main rail; means spacing the guard rail from the main rail; wedge devices placed at intervals along the guard rail adapted, when the guard rail is in one position lengthwise of itself, to engage the brace blocks and secure the guard rail thereto while permitting ready removal of the guard rail from the brace blocks when the guard rail is moved lengthwise of itself to a certain other position, and supplemental means for preventing loosening of the wedge devices.
10. In a device of the class described, the combination with a main rail and the ties supporting the same; a base plate extending over several of the ties inserted under the rail; means for securing the base plate to the ties; a plurality of brace blocks rising from the base plate on one side of the rail spaced at intervals one from the other and from the main rail, there being slots cut in the brace blocks open toward the rail, the tops of said slots being parallel to the axis of the main rail; wedge faces formed on the brace blocks at an angle to the central axis of the main rail; a guard rail adapted to rest upon and be supported by the brace blocks having along its length projections entering said slots in the brace blocks; wedge surfaces on the guard rail adapted to engage said wedge surfaces on the brace blocks; a spacing member extending from the guard rail to the main rail; and means for rigidly securing all of the parts in position when the wedge members have been driven into engagement with each other.
11. In a device of the class described, in combination with a main rail and the ties supporting the same; a base plate extending over several of the ties inserted under the rail; means securing said base plate to the tie; a plurality of brace blocks rising from the base plate on one side of the rail spaced at intervals one from the other and from the main rail, there being slots cut in the brace blocks open toward the rail, the tops of said slots being parallel to the axis of the main rail.

5 rail; wedge faces formed on the brace blocks at an angle to the central axis of the main rail; a guard rail of angular cross-section adapted to rest upon and be supported by
10 the brace blocks with one side of the angle lying over and resting upon the brace block, the other side of the angle forming a vertical member substantially parallel to the main rail, said guard rail being slidable within limits lengthwise of the brace blocks; wedge faces formed at intervals along the under side of the horizontal side of the angular guard rail, one for engagement with each of the wedge faces of the brace blocks;
15 correspondingly located flanges extending from the vertical side of the guard rail entering and adapted to slide in said slots in the brace blocks; means extending from the

guard rail to the main rail to space it therefrom; and means for rigidly locking the parts in final assembled position, the lengths of the last mentioned flanges on the guard rail being such that when the guard rail is moved a given distance lengthwise of itself, these flanges cease to engage the brace blocks and the guard rail and attached parts may be removed from working position with reference to the main rail and brace blocks.

In witness whereof, I have hereunto subscribed my name in the presence of two witnesses.
